UNITED STATES PATENT OFFICE

FREDERICK E. MILLER, OF WENATCHEE, WASHINGTON

SCANNING DISK

Application filed June 27, 1930. Serial No. 464,405.

This invention has reference to electric transmission of views or pictures to a distant point and particularly to television.

An object is the provision of simple means for bringing a televised view, picture, or image in focus (or squaring the same as it is usually termed) after the image has been synchronized.

A further object is the provision of a means for this purpose in which the scanning disk is centrally mounted on the shaft of a motor and supported in bearings whereby the motor and disk can be simultaneously turned in the bearing so that the televised vision may be brought to the exact position or square with respect to the frame of the picture without interfering with the speed of the motor or the speed of the scanning disk.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claims.

In the drawings:

Figure 1 is a side elevation of the improvement.

Figure 2 is a sectional view approximately on the line 2-2 of Figure 1.

Figure 3 is a plan view of the improvement.

Figure 4 is a rear end view thereof.

As the art to which my invention relates is fully understood by those interested in television detail mention thereof is not believed necessary nor is it thought necessary to disclose the casing in which the scanning disk may be arranged, the lens from which the rays of light that pass through the apertures of the disk are transmitted nor other details

of construction other than those relating to my particular invention.

As disclosed by the drawings the improvement includes a suitable base 1 from which there arises one or more bearings 2. In the showing of the drawings only a single bearing is provided and through this bearing there is passed the round or nose end 3 for the casing 4 of an electric motor. As disclosed by Figure 2 of the drawings the bearing support 2 is constructed from a single piece of suitable material bent upon itself to provide the rounded bearing proper and formed with depending normally parallel legs 2' whose lower ends are offset to provide feet that are attached to the base 1. There is passed through suitable alining openings in the legs 2' a bolt 11 which is engaged by a nut 12. The bolt, when adjusted on the screw will force the legs 2' together, and consequently compress the round bearing 2 against the nose 3. This frictional contact is sufficient to prevent the accidental or free turning of the motor in its bearing. The shaft of the motor is indicated by the numeral 5 and to the outer end of this shaft there is centrally fixed the scanning disk 6. As disclosed by the drawings the scanning disk is provided with a spirally arranged series of spaced small openings 7 for the light rays. The motor on the end thereof opposite that provided with the nose is provided with a round extension 8 provided with a round handle 9 which is preferably peripherally knurled. This end of the motor casing has fixed thereto the vertical arm of a substantially L-shaped member 9', the longitudinal arm of the said bracket being in the path of contact with a pivotally supported stop member 10 whose pivoted end is received in a depression in the base 1. As disclosed by Figure 4 of the drawings the pivot 13 for the stop member 10 is arranged in a line with the vertical center of the motor 4, as is the L-shaped member 9'. Also as disclosed by the said figure the opposite end walls 14 provided by the depression 15, in which the lower end of the stop member 10 is received, are arranged at opposite angles with respect to each other, each of said walls being struck at an angle of approximately 45°.

As stated there is a frictional contact between the bearing 2 and the nose of extension 3 of the motor casing which, however, is not sufficient to prevent the operator from turning the motor through the instrumentality of the handle 9 to adjust the scanning disks to the relative phase positions required for the proper framing of the images. The bearing mount for the motor is so arranged that stator structures are such that the same may be rotated throughout a portion of a revolution of the motor to adjust the phase position of the scanning disk to obtain the proper framing of the image. The motor may be turned a complete revolution in either direction and halted when such revolution is completed. As disclosed by Figure 4 of the drawings the angle end of the member 9' is in contact with one of the edges of the stop member 10 and therefore the motor cannot be revolved in the direction of the said stop 10. The motor, however, can be turned in a second direction or away from the stop and when the same has completed a revolution the angle end of the member 9' will contact with the second or outer edge of the stop 10, swinging the said stop to the dotted line position in said Figure 4 to cause the stop to rest upon the second angle end wall 14 provided by the depression 15. Thus the stator structure may be given a complete revolution in either of two directions.

Having described the invention, I claim:

1. A picture transmitting or receiving apparatus, including a rotary scanning disk, and a current driven motor on whose shaft the disk is fixed, a base having a support affording a bearing for the motor casing adjacent the scanning disk, and the casing having its second end provided with a knob, a depending substantially L-shaped member fixed on the said end of the motor, and a pivotally supported stop element in the base extending thereabove for contact with either side of the angle end of the bracket to cause a limited swinging of the stop element when the motor is imparted a complete revolution in one direction and such engagement of the angle member with the swingable stop preventing the turning of the motor in the direction of the stop susceptible for being sprung away from such contact.

2. A picture transmitting or receiving apparatus which includes a rotary scanning disk and a current driven motor on whose shaft the disk is fixed and the casing for the motor having its ends provided with rounded extensions, a compressible bearing support carried by the base for the rounded extension of the casing adjacent the scanning disk, means for adjustably compressing the bearings, a knurled operating head on the end of the second casing extension, a member having an angle end depending from said extension, the base having a substantially V-shaped recess,

a stop finger having one end received and pivotally secured in the recess and its outer end in the path of contact with the angle end of the member, as and for the purpose set forth.

In testimony whereof I affix my signature. 70
FREDERICK E. MILLER.
